UNITED STATES PATENT OFFICE.

RUFUS H. GRANT, OF WESTBROOK, MAINE, ASSIGNOR TO RICE, BARTON & FALES, INCORPORATED, OF WORCESTER, MASSACHUSETTS, A CORPORATION OF MASSACHUSETTS.

PAPER-MAKING MACHINE.

Application filed February 2, 1924. Serial No. 690,230.

To all whom it may concern:

Be it known that I, RUFUS H. GRANT, a citizen of the United States, and a resident of Westbrook, Maine, have invented 5 new and useful Improvements in Paper-Making Machines, which invention is fully set forth in the following specification.

This invention relates to improvements in Fourdrinier paper making machines and more particularly to the supporting and vibrating of the shake-frame or shaking section.

Heretofore it has been common practice to support the shake-frame by upright spring bars located at opposite sides of the machine. Each such support consists either of a single flat steel spring, or a plurality of such springs or laminations of equal width and length, attached at one end to the shake-frame and at the other end rigidly secured to a suitable support and admitting of the necessary shaking or vibration of the shake-frame by means of the usual power driven means including a pitman or connecting rod joined at one end to said shake-frame. In conjunction with such supporting of the shake-frame there have also been provided adjustable oppositely acting coiled springs mounted underneath the forward end of the shake-frame, as shown for example in Savery Patent 675,072, May 28, 1901, and Mellinger et al Patent 1,118,366, Nov. 24, 1914. One function of such coiled springs is to cushion or absorb the shock 35 of stopping the large inertia shake-frame at the end of each vibration thereof, such frames with the parts carried thereby ranging in weight as high as seventeen tons. Another function is to assist and render 40 the shaking action as sensitive and easy as possible and to that end it has been the intention to maintain an adjustment of said coiled springs such as to create constant tension upon the connecting rod of the 45 aforesaid power driving connections in both directions of vibration of the shake-frame and to thereby also admit of the use of a relatively light or small diametered connecting rod. In other words, it has been 50 the purpose to vibrate the shake-frame in one direction by the pull of the connecting rod and in the other direction by the action of the coiled springs, and to thereby avoid load, strain and wear upon the driving 55 connections and bearings thereof which

would be occasioned by requiring thereof both a pulling of the shake-frame in one direction and then a pushing of the same in the opposite direction. While plausible in theory these coiled spring arrangements 60 have not worked out well in practice and hence have been unsatisfactory. Experience has demonstrated that the coiled springs continually get out of adjustment 65 and that when thus not "tuned up" they are, if anything, more detrimental than helpful. Furthermore, being inaccessibly located under a wet part of the machine, such springs can only be reached for readjustment by interfering with and shutting 70 down the running of the machine normally intended to run continually except on Sundays.

Some of the main objects sought and attained by the present invention are to overcome the aforesaid difficulties and generally to simplify and improve upon said prior mechanism both as to construction and operation; to minimize the driving power required to vibrate the shake-frame and also 75 the wear upon parts and bearings; to provide an arrangement in which the springs are at all times readily accessible and easily adjustable while the machine is running and without interruption to the operation thereof; to combine in one set of springs the functions of both the flat steel supporting springs and the coiled springs heretofore used, preferably employing to that end 80 specially constructed springs of the leaf or laminated type such as commonly used on automobiles and other vehicles. A further object attained in the securing of the springs at their fixed ends each in special supports each adjustable on a horizontal 85 axis to thereby tension each spring as required with relation to the shake-frame and the connecting rod of the power driving means. Still other objects and advantages 90 attained by the invention will be apparent 95 from the further description and drawings. 100

What is at present believed to be the preferred mechanical expression and embodiment of the invention is illustrated in the 105 accompanying drawings, wherein—

Fig. 1 is a side elevation showing particularly the shaking section of the Fourdrinier part of a paper making machine;

Fig. 2 is an end elevation looking toward 110 the right from the left end of Fig. 1;

Fig. 3 is a view similar to Fig. 2 but on a larger scale and with parts in section;

Fig. 4 is a fragmentary side elevation of one end of the shaking section shown in Figs. 1 to 3;

Fig. 5 is a top view of the parts shown in Fig. 4;

Fig. 6 is a sectional view on line 6—6 of Fig. 7; and

Fig. 7 is a fragmentary view in elevation illustrating particularly the supporting of the table rolls and their bearings from the shake rails.

As shown in the drawings, the shaking section or shake-frame of the machine comprises in the main a U-shaped frame 10 extending across the machine and connecting the forward ends of two longitudinal side rails 11 and 12, table rolls 30 carried by said side rails which are also called shake rails, and a breast roll 40 (shown in dotted lines Figs. 1 and 2) over which runs the Fourdrinier or making wire (also shown in dotted lines Fig. 1). The frame 10 is of elongated U-shaped formation and includes upright legs 13 and 14 at its opposite ends. To stiffen the side rails and also the shaking section as an entirety, struts and other bracing means are provided. Thus a strut bar 15 extends longitudinally of each rail with an interposed brace 16 at one end and an interposed rectangular frame or casting 17 at the other end. Each shake rail at its inner end (in the direction of the travel of the making wire indicated by dotted lines in Fig. 1) is pivotally supported on a suitable part of the framework. Thus a vertical pivot 18 connects the rail to a block 19 which in turn is horizontally pivoted at 20 to the upper end of a frame standard 21. Each side rail can vibrate or shake laterally on its pivot 18, and can turn on the horizontal pivot 20 when raised or lowered at its forward end in adjusting the inclination of the entire shake frame.

At its forward end each rail 11 and 12 is rotatably supported on a swivel plate 22 supported upon the upper end of the corresponding leg 13 or 14 of the U-shaped frame 10. A spindle 23 extending vertically through each leg 13 and 14 passes at its upper end through a bushing 24 socketed in the upper end of the arm, then through the swivel plate 22 and the shake rail 11 or 12 and on the top side of the latter is engaged by a nut 25 which is covered by a cap 26. A head or sleeve 27 at the lower forward edge of each casting 17 projects into a recess 28 at the lower end of the corresponding leg 13 or 14 of the U-shaped frame 10 and is there traversed by and rotatable on the spindle 23. As thus appears, said U-shaped frame 10 and the side rails 11 and 12 and associated parts may be vibrated or shaken laterally at the forward ends of said rails

which turn at their rear ends on their vertical pivots 18 and at their forward ends on the spindles 23.

The table rolls 30 may be supported from the side rails in any suitable manner. As shown in the drawing each rail has suitably spaced depending brackets 31 bolted to its under side and supporting a bar 32 which carries journals for the rolls. The bar may be adjusted up or down by set screws one on each bracket 31, a bolt 34 working in a slot of each bracket serving to rigidly secure the bar in the position to which it is adjusted.

Breast roll 40 is journalled at opposite ends in bearings 41 and 42 adjustably secured respectively to the front faces of the legs 13 and 14 of the U-shaped frame 10. Each bearing is secured in place by two bolts 43 which pass through vertical elongated slots 44 in the corresponding leg 13 or 14 and may be raised or lowered by an adjusting screw 45 threaded through a bracket 46 on the leg of the frame 10, the head of such adjusting screw contacting an over-hanging ledge 47 on the bearing and the bolt having a lock nut 48 for locking it in adjusted position. At 49 (Fig. 1) there is shown in dotted outline a flow-box, which may be of any suitable construction.

50 is a block movable vertically along a flat surface of each leg 13 and 14 of the U-shaped frame 10 and constituting a seat for the upper end of one of the upright springs which are to support the forward end of the shaking section of the machine. Said block 50 is penetrated by a bolt 51 the headed inner end of which is slideable in an undercut slot in the surface along which the block 50 is adjustable. A clamp plate with nuts screw threaded onto the outer end of bolt 51 serve to rigidly clamp the upper end of the supporting spring and the block 50 to the frame 10 in the desired position of adjustment. To change that position the nuts are loosened and an adjusting screw 52, bearing on the top surface of the block 50, is turned either to elevate the shaking section or to permit the same to lower by its own weight, thus changing the elevation of the forward end of the shaking section and correspondingly varying its inclination.

55, Fig. 2, represents any suitable power driven means sometimes called the shake-head, for imparting shaking movement to the shaking section or shake-frame through a connecting rod or pitman 56 pivotally connected to a clamp block or collar 57 (Figs. 4 and 5) which embraces a slightly curved cylindrical rod 58 in such manner that said rod may slide vertically up or down through said block 57 when the elevation of the forward end of the shake section is changed by raising or lowering the connection to the

- supporting springs by means of the adjusting screws 52, 52 and associated parts as hereinbefore described. At this upper end rod 58 is rigidly secured in a projecting lug 59 on the leg 14 of the U-shaped frame 10, and at its lower end seated and rigidly secured in a socket at the outer end of a curved arm 60 also located on said leg 14 of the frame 10.
- 10 The parts hereinbefore mentioned in the detailed description (with the exception of the springs) may be of any well known and suitable construction such as illustrated. The present invention concerns more particularly the springs for supporting the forward end of the shaking section or shake-frame and other parts of which the following is a detailed description.
- 15 65 and 70 are the upright springs for supporting the forward end of the shaking section or shake-frame of the machine in a manner permitting lateral vibration or shaking thereof. Each of said springs is of the leaf or laminated type somewhat of the character of such springs as used on automobiles and other vehicles. The spring 65 is at the side of the machine at which the connecting rod 56 imparts vibration to the shaking section, in other words at what is known as the "driving side" of the machine, while the spring 70 is positioned at the opposite or what is known as the "tending side." As shown, said spring 65 is made up of a succession of laminations or leaves 20 of uniform width but gradually increasing length beginning with the shortest leaf at the outer side of the spring, there being four of these graduated length leaves with the fourth lying against one of three longest leaves of which all are of equal length and clamped at their upper ends to the block 50 by the bolt 51 which passes through openings in the upper ends of said leaves.
- 25 40 As shown, the spring 70 is also made up of a plurality of laminations or leaves of uniform width but varying lengths. Thus there are three centrally positioned longest leaves all of equal length and clamped at their upper ends to their corresponding block 50 by its bolt 51 which passes through openings in the upper ends of said leaves. There are next two shorter leaves positioned one against each of the outside longest leaves, and then two more still shorter leaves 30 positioned one against each of the first mentioned shorter leaves respectively.
- 35 55 75 is a seat or support for the lower end of spring 65, the plurality of leaves of the latter being rigidly clamped together at their lower ends to said support by bolt 76 passing through an upright flange of said support through the lower ends of all of said spring leaves, and through two clamping blocks 77 and 78 located at opposite sides 40 respectively of the group of spring leaves.
- The support 75 is horizontally pivoted between upstanding lugs or ears 79, 80 of a base bracket 81, on a horizontal trunnion or bolt 82 extending through said ears and support. Two adjusting screws 83, 83 with bolt heads, pass freely downwardly through holes in an extension or plate 84 on the support 75 and at their lower ends engage screw threaded sockets in a base plate 85. A third adjusting screw 86 also having a bolt head 75 makes screw threaded engagement through said extension or plate 84 and at its lower end bears against the surface of said base plate 85. As will thus be apparent, these three adjusting screws serve to effect a rocking or tilting adjustment of the support 75 on its pivot 82 and to rigidly hold the support in any position to which it is thus adjusted. For example, to adjustably tilt or rock the support toward the right in Fig. 85 3, the two adjusting screws 83, 83 would be unscrewed and the adjusting screw 86 screwed up each the proper amount to give the desired adjustment.
- 45 The support 75 and associated parts thus described with reference to spring 65 are duplicated at the other side of the machine with respect to the spring 70.
- 50 90 95 99 100 105 110 115 120 125 130 90, Figs. 2 and 3, is a heavy beam extending across the machine between the two base plates 83, 83 and constituting a part of the general framework.
- 100 In operation, the supports 75, 75 are set or adjusted to such position—by means of their readily accessible adjusting screws 83, 83 and 86—as to place the springs 65 and 70 under tension toward the tending side of the machine (to the right in Figs. 2 and 3) and thereby constantly exert pressure upon the shake-frame in that direction with a resultant constant pull or tension upon the connecting rod 56 of the driving connections. It follows that while the shake-frame will be vibrated in one direction by the pull of the driving means through the connecting rod 56 against the opposing tension of said springs, it will be vibrated in the other direction by the reacting tension of said springs and not by a pushing force of the power driving connections exerted through the connecting rod. The leaves at the left side of each of the springs 65 and 70 in Figs. 2 and 3 are important in affording the necessary spring power for thus vibrating the shake-frame in one direction of its movement and without which spring power the driving connections would be required to push the shake-frame in that direction after having pulled it in the opposite direction, with resulting strain and rapid wear upon the parts requiring frequent repairs. It is important that any tendency towards looseness of connections or slackening of constant tension upon the connecting rod shall be promptly avoided.

by readjustment of the springs, thereby avoiding undue strain or wear which would otherwise result. The springs 65 and 70, also serve the necessary and important function of cushioning the stopping of the weighty shake-frame at the end of each vibration thereof and on this point the leaves of graduated length at the right side of spring 70, Figs. 2 and 3, are especially important. It has been demonstrated in practice that without some such means of spring compensation that the load or force at each end of the stroke falls like a hammer blow upon the connecting rod and that the pins and bushings of movable parts are quickly worn out causing the equipment to get loose and necessitating frequent repairs.

What I claim is:

1. In a paper making machine, the combination of a laterally vibratory shake-frame; driving connections joined to said shake-frame for imparting lateral movement thereto; means supporting said shake-frame and permitting lateral vibration thereof, said means including an upright spring supporting bar secured at one end to said shake-frame and at its other end to a suitable support and said spring bar being tensioned to constantly tend to move the shake-frame to the limit of its vibration in one direction and thereby imposing tension upon said driving connections throughout movement of the shake-frame in both directions of its vibration.
2. In a paper making machine, the combination of a laterally vibratory shake-frame; driving connections joined to said shake-frame for imparting lateral movement thereto; means supporting said shake-frame and permitting lateral vibration thereof, said means including an upright spring supporting bar at one side of the shake-frame secured at its upper end to said frame and at its lower end to a suitable support and said spring bar being tensioned to constantly tend to move the shake-frame to the limit of its vibration in one direction and thereby imposing tension upon said driving connections throughout movement of the frame in both directions of its vibration.
3. In a paper making machine, the combination of a laterally vibratory shake-frame; driving connections joined to said shake-frame at one side thereof for imparting lateral movement thereto; means supporting said shake-frame and permitting lateral vibration thereof, said means including an upright spring supporting bar secured at one end to said shake-frame and at its other end to a suitable support and said spring bar being tensioned to constantly tend to move the shake-frame to the limit of its vibration in the direction opposite the side thereof to which the driving connections

are joined and thereby imposing tension upon said driving connections throughout movement of the shake-frame in both directions.

4. In a paper making machine, the combination of a laterally vibratory shake-frame; driving connections including a connecting rod joined to said shake-frame at one side thereof for imparting lateral movement thereto; means supporting said shake-frame and permitting lateral vibration thereof, said means including one or more upright spring supporting bars each secured at its upper end to said shake-frame and at its lower end to a suitable support and said spring bar or bars being tensioned to constantly tend to move the shake-frame to the limit of its vibrations in the direction opposite the side thereof to which the connecting rod is joined and thereby imposing tension upon said driving connections throughout movement of the shake-frame in both directions.

5. In a paper making machine, the combination of a laterally vibratory shake-frame; driving connections joined to said shake-frame for imparting lateral movement thereto; means supporting said shake-frame and permitting lateral vibration thereof, said means including an upright spring supporting bar at each side of the shake-frame secured at its upper end to said frame and at its lower end to a suitable support and said spring bars being tensioned to constantly tend to move the shake-frame to the limit of its vibration in one direction and thereby imposing tension upon said driving connection throughout movement of the shake-frame in both directions of its vibration.

6. In a paper making machine, the combination of a laterally vibratory shake-frame; driving connections joined to said shake-frame at one side thereof for imparting lateral movement thereto; means supporting said shake-frame and permitting lateral vibration thereof, said means including an upright spring supporting bar at each side of the shake-frame secured at its upper end to said shake-frame and at its lower end to a suitable support and said spring bars being tensioned to constantly tend to move the shake-frame to the limit of its vibration in the direction opposite the side thereof to which the driving connections are joined and thereby imposing tension upon said driving connections throughout movement of the shake-frame in both directions.

7. In a paper making machine, the combination of a laterally vibratory shake-frame; driving connections joined to said shake-frame for imparting lateral movement thereto; and one or more upright spring bars connected at one end to said

shake-frame and at the other end to a suitable support, said spring bar or bars being tensioned to constantly tend to move the shake-frame to the limit of its vibration in one direction and thereby imposing tension upon said driving connections throughout movement of the shake-frame in both directions of its vibration.

8. In a paper making machine, the combination of a laterally vibratory shake-frame; driving connections joined to said shake-frame for imparting lateral movement thereto; and one or more upright spring bars connected at one end to said shake-frame and at the other end to a suitable support, each bar being composed of a plurality of leaves of varying lengths and being tensioned to constantly tend to move the shake-frame to the limit of its vibration in one direction and thereby imposing tension upon said driving connections throughout movement of the shake-frame in both directions of its vibration.

9. In a paper making machine, the combination of a laterally vibratory shake-frame; driving connections joined to said shake-frame for imparting lateral movement thereto; means supporting said shake-frame and permitting lateral vibration thereof, said means including an upright spring supporting bar secured at one end to said shake-frame and at its other end to a suitable support, said spring bar being composed of a plurality of leaves of varying lengths and being tensioned to constantly tend to move the shake-frame to the limit of its vibration in one direction and thereby imposing tension upon said driving connections throughout movement of the shake-frame in both directions of its vibration.

10. In a paper making machine, the combination of a laterally vibratory shake-frame; driving connections joined to said shake-frame for imparting lateral movement thereto; means supporting said shake-frame and permitting lateral vibration thereof, said means including an upright spring supporting bar at each side of the shake-frame secured at its upper end to said frame and at its lower end to a suitable support, and each of said spring bars being composed of a plurality of leaves of varying lengths and being tensioned to constantly tend to move the shake-frame to the limit of its vibration in one direction and thereby imposing tension upon said driving connections throughout movement of the shake-frame in both directions of its vibration.

11. In a paper making machine, the combination of a laterally vibratory shake-frame; driving connections joined to said shake-frame for imparting lateral movement thereto; and a spring bar secured at one end to said shake-frame and at its other end to a suitable support, said bar being

composed of a plurality of leaves of varying lengths.

12. In a paper making machine, the combination of a laterally vibratory shake-frame; driving connections joined to said shake-frame for imparting lateral movement thereto; and a spring bar secured at one end to said shake-frame and at its other end to a suitable support, said bar being composed of a plurality of leaves of varying lengths at both sides thereof.

13. In a paper making machine, the combination of a laterally vibratory shake-frame; driving connections joined to said shake-frame for imparting lateral movement thereto; and an upright spring supporting bar for said shake-frame secured at its upper end to said frame and at its lower end to a suitable support, said bar being composed of a plurality of leaves of varying lengths.

14. In a paper making machine, the combination of a laterally vibratory shake-frame, driving connections joined to said shake-frame for imparting lateral movement thereto; and upright spring supporting bars for said shake-frame one at each side thereof and at their upper ends secured to said frame, each of said bars being composed of a plurality of leaves of varying lengths.

15. In a paper making machine, the combination of a laterally vibratory shake-frame; driving connections joined to said shake-frame for imparting lateral movement thereto; an upright spring bar; means connecting said bar at one end to said shake-frame and at its other end to a suitable support, said means including an adjustable seat in which one end of said spring bar is secured; and means for adjusting said seat to tension said spring bar in one direction of vibration of the shake-frame.

16. In a paper making machine, the combination of a laterally vibratory shake-frame; driving connections joined to said shake-frame for imparting lateral movement thereto; means supporting said shake-frame and permitting lateral vibration thereof, said means including an upright spring supporting bar; means connecting said bar at one end to said shake-frame and at its other end to a suitable support and said means including an adjustable seat in which one end of said spring bar is secured; and means for adjusting said seat to tension said spring bar in one direction of vibration of the shake-frame.

17. In a paper making machine, the combination of a laterally vibratory shake-frame; driving connections joined to said shake-frame for imparting lateral movement thereto; an upright spring bar connected at its upper end to said shake-frame; an adjustable seat to which said bar is se-

cured at its lower end; and means for adjusting said seat to tension said spring bar in one direction of vibration of the shake-frame.

5 18. In a paper making machine, the combination of a vibratory shake-frame; a spring bar joined at one end to said frame and at its other end secured in a seat mounted on a suitable support; and means 10 for adjusting the position of said seat to tension said spring bar.

19. In a paper making machine, the combination of a vibratory shake-frame; an upright spring supporting bar for said frame joined at its upper end to the frame; a seat 15

to which the lower end of said spring bar is secured; and means for adjusting the position of said seat to tension said spring bar.

20. In a paper making machine, the combination of a vibratory shake-frame; an upright spring bar joined at its upper end to said shake-frame; a seat adjustable on a pivot and to which seat said spring bar is secured at its lower end; and means for adjusting said seat on its pivot to thereby tension said spring bar.

In testimony whereof I have signed this specification.

RUFUS H. GRANT.
